UNITED STATES PATENT OFFICE.

JAMES C. KIMSEY, OF PHILADELPHIA, PENNSYLVANIA.

COMBINED SKIRT-SUPPORTER AND WAIST-HOLDER.

SPECIFICATION forming part of Letters Patent No. 657,425, dated September 4, 1900.

Application filed May 12, 1900. Serial No. 16,504. (No model.)

To all whom it may concern:

Be it known that I, JAMES C. KIMSEY, a citizen of the United States of America, residing at Philadelphia, in the county of Philadelphia and State of Pennsylvania, have invented 5 new and useful Improvements in a Combined Skirt-Supporter and Waist-Holder, of which the following is a specification.

This invention is an improvement upon the 10 combined skirt-supporter and waist-holder shown and described in my prior patent, No. 636,149, dated October 31, 1899; and the objects of the present invention are to simplify the construction of the device in order that 15 it may be more cheaply made and permit shorter pins or points to be used for engagement with the waist.

With these objects in view the present invention consists in the peculiar construction 20 of the plate and pins which are carried thereby, all as will be hereinafter fully described, and specifically pointed out in the appended claims.

In the accompanying drawings, which form 25 a part of this specification, Figure 1 is a perspective view of a combined skirt-supporter and waist-holder constructed in accordance with my invention. Fig. 2 is a sectional view. Fig. 3 is a sectional view illustrating 30 the shape of the pin before it is bent into locked engagement with the plate. Fig. 4 is a detail view of one of the pins or wires.

Referring to said drawings, A designates the plate, which is provided at its ends with 35 vertical slots a, through which the supporting-belt B is passed. The lower edge of the plate A is cut away at intervals, as shown, to provide openings C, which form outwardly-curved side edges c and an inner straight 40 edge c'. On a line with each opening C holes a' and a² are formed in the plate, the hole a' being closely adjoining the inner end of the opening, while the hole a² is in the upper part of the plate.

45 D D' designate short lengths of wire or double-pointed pins, the ends of which are passed through the holes a' and a² from the inner side of the plate A, presenting points or spurs d and d', the spurs d being inclined upward from the outer side of the plate, while the spurs d' project downward and rearward through the openings C and extend beyond

the rear side of the plate. This peculiar manner of attaching the pins or wires forms spurs projecting in opposite directions from the 55 front and rear sides of the plate to engage the skirt and waist, respectively, and each pair of spurs d and d' are formed from a single pin or wire.

The lower ends of the slots a are on a line 60 with the upper ends of the openings C in order that the lower edge of the belt or band which is passed through said slots will be located above the points or spurs d', the latter being of such length as to project slightly beyond 65 the lower edge of the belt. The said belt is of sufficient width to cover that part of the wires or pins which lies against the inner side of the plate, between the holes a' and a².

In order to facilitate the operation of attaching the pins, said pins are shaped as shown in Fig. 4, presenting a straight portion, from the upper end of which the spur d extends at a slight downward inclination, while the oppositely-projecting spur or lower end d' is 70 connected to the straight portion by a double bend d². In attaching the pin the lower end or spur d' is passed through the hole a' of the plate, the pin being then brought forward and the upper spur d passed through the hole 75 a², the said pin assuming the position illustrated in Fig. 3, with the spur d projecting at a slight downward inclination from the front side of the plate and the spur d' projecting rearward through the opening C, Fig. 80 3, after which the said spur d is bent upward to its proper position and locks the pin securely in place.

The supporting band or belt is fastened around the waist by means of a buckle E, 90 consisting of a metal loop through which the other end of the belt is passed, said loop having prongs e with which the band is adapted to engage.

In applying the device the waist or upper 95 garment is pulled down in the back behind the plate A and caused to engage with the lower points or spurs d', and after the belt is fastened the skirt-band is placed in engagement with the upper spurs or points d. 100 The skirt and waist are thereby held securely in place, and the upper part of the skirt practically hides the device.

It will be noted that the part of the skirt-

waist which engages the pins d' will be gathered into the openings C and bind in the upper part thereof, increasing the hold upon the garment and reducing its liability to tear, 5 the curved edges of the opening serving to gather the material into the same. It is only necessary, therefore, that the pins or points d' project very slightly beyond the lower edge of the belt or band, and as these pins or points 10 project inward or toward the body of the wearer they will not prick the body.

The present invention is an improvement over that shown in my prior patent hereinbefore referred to, as it can not only be more 15 cheaply manufactured, but is also more effective in use.

A comparatively-thin plate may be used, and the pins or wires are of the proper gage to give the required strength and rigidity to 20 the points or spurs. In some instances I may have the lower edge of the plate straight instead of providing the openings C , in which case the lower pins or spurs would project rearwardly under the lower edge in the same 25 manner as they project through the said openings; but the openings are preferred, as they are more effective, as hereinbefore noted.

Having thus described my invention, what I claim as new, and desire to secure by Letters 30 Patent, is—

1. A combined skirt-supporter and waist-holder, comprising a plate having a series of hooks projecting upwardly from the face of the plate near the upper edge of the same, 35 and a series of hooks projecting from the same side near the lower edge of the plate downwardly and rearwardly to and beyond the op-

posite face of said plate, substantially as shown, together with the supporting-belt.

2. A combined skirt-supporter and waist-holder, comprising a plate having holes through the upper and lower portions thereof, and a series of wires having pointed ends d and d' passed through said holes from one side of the plate and bent in opposite directions, one of the points being bent rearward under the edge of the plate to form a point or hook on the opposite side of the plate from the other hook and projecting in an opposite direction therefrom; together with the supporting-belt to which the plate is attached, substantially as shown and for the purpose set forth.

3. A combined skirt-supporter and waist-holder, comprising a plate having holes through the upper and lower portions thereof and cut away at one edge to form openings C on a line with said holes, and a series of wires D having pointed ends d and d' passed through said holes from the rear side of the plate and bent in opposite directions in front of said plate, one of the points of each wire being further bent to project through the adjoining opening C beyond the rear side of the plate; together with the supporting-belt to which the plate is attached, substantially as shown and for the purpose set forth.

In testimony whereof I affix my signature in presence of two witnesses.

JAMES C. KIMSEY.
